UNITED STATES PATENT OFFICE.

HOWARD L. FISCHER, OF ST. PAUL, MINNESOTA.

PENCIL.

Application filed December 27, 1920. Serial No. 433,113.

To all whom it may concern:

Be it known that I, HOWARD L. FISCHER, a citizen of the United States of America, residing at St. Paul, in the county of Ramsey and State of Minnesota, have invented certain new and useful Improvements in Pencils, of which the following is a specification.

This invention relates to pencils, the primary feature of which is to provide a mechanical pencil the operating mechanism of which is sectionally associated together so that the different sections can be removed separately from the pencil barrel or casing for refilling the pencil or for replacing the parts. The operating mechanism of this pencil can be entirely removed from the casing to leave the same empty. This allows the interchanging of parts or of the entire mechanism without changing the barrel.

A feature of the invention is in a pencil composed of very few simple parts including namely; a casing or barrel, a threaded member and an operating member and each of these parts are separable from each other, or the threaded and operating member can be removed collectively.

This invention includes primarily a simple spring lock between the operating member and the threaded member. The lock is carried by the operating member, being freely rotatable on the same, when the operating member and threaded member are separated. The spring lock frictionally engages under spring tension, the smooth rear end of the threaded member, and remains stationary during the rotation of the operating member when the propelling means is in operation.

The invention also includes an engaging head on the operating member adapted to contain and conceal an eraser and of a design to be spaced from the closure for the rear end of the pencil magazine which locks the threaded member in the barrel or casing.

In the drawings forming a part of this specification:

Figure 1 illustrates my pencil.

Figure 2 is an enlarged longitudinal cross sectional view of the pencil.

Figure 3 illustrates the threaded member removed from the pencil and partly shown in cross section.

Figure 4 is an enlarged view of the operating member of the pencil.

Figure 5 is a detail of the rear end of the

operating member, a portion of which is removed.

Figure 6 is a perspective view of the spring locking sleeve removed from the operating member.

The pencil A is formed with a tubular barrel or casing 10 the forward end 11 of which is swaged to a conical shape to simulate the writing end of an ordinary pencil. The pencil A is designed primarily to use a marking lead of a very small diameter and the end 11 is formed at the apex with an opening 12 which is of a slightly greater diameter than the marking lead 13 used in the pencil.

The lead propelling mechanism B is secured in the casing A in a manner to propel or repel the marking lead 13. The mechanism B is positioned in the casing 10 so as to form a circular magazine thereabout for extra marking leads, the forward end of the same being spaced from the casing by the washer member 14 and the rear end is attached and secured to the casing by the threaded closure collar 15. The mechanism B is formed of sections consisting of the threaded tubular member 16 to which the washer 14 and the closure 15 are secured and the operating member C, which is removable from the member 16.

The operating or cap member C is composed of the tubular longitudinally slotted member 17 which carries the lead pushing member 18. The member 18 is held in the member 17 so that it will engage the threads of the member 16 in a manner to propel or repel the marking lead in writing position in the pencil and is provided with spring arms 19 and 20 which cause it to engage the threads under spring tension.

The lead socket 21 is formed for receiving the butt end of the marking lead 13 on the finger 20. The spring arms 19 and 20 of the lead carrier 18 provide sufficient friction between the member 17 and the threaded member 16 to prevent free longitudinal movement of the same, however, in a backward or repelling operation of the mechanism B owing to the friction caused by the lead carrier 18 between the members, the member 17 has a tendency to unscrew or back out of the member 16. To overcome this action a spring sleeve lock E is secured to the member 17 of the operating or cap member C.

The lock E consists of the spring collar 22 which is constricted on its ends and is formed

with a longitudinal slit to divide the same so that it will readily compress or expand and is adapted when the operating member C is inserted in the threaded member 16 to be 5 compressed and engaged with considerable friction against the inner unthreaded portion 23 of the member 16.

The collar 22 is held by the shoulders 24 and 25 freely rotatable on the member 17 10 adjacent the inner end 26 of the engaging head of the operating member C. When the operating member C is inserted into the member 16 the spring sleeve 22 is engaged by the member 16 and is held against rotation while the sleeve 22 engages the member 16 with considerable friction, yet owing to its resiliency it is readily withdrawn when it is desired to separate the operating member C from the threaded member of the propelling mechanism B. The lock E prevents the operating or cap member C from moving longitudinally in the propelling mechanism during its operation, the friction of the lock E overcoming the tendency of the lead carrier 18, forcing the operating member C out 20 of the propelling mechanism when being operated to repel the marking lead.

The operating or cap member C is provided with an engaging head 27 which is in 30 the form of a cap adapted to engage the outer surface of the eraser receiving socket 28 under friction. An eraser 29 is concealed beneath the cap or head 27 and fits within the socket 29.

35 The propelling mechanism B is positioned in the casing 10 in a manner to form a circular magazine chamber 30 about the threaded portion 16 which is closed on the forward end by the member 14 and on the rear end by the closure 15. Extra marking leads 13 are adapted to be contained in the magazine chamber.

When it is desired to place a new marking lead in the socket 21 the operating member 45 C is withdrawn from the member 16 either by a backward rotation and pull on the head 27 or by a straight longitudinal non-rotary pull in a backward direction on the same. The cap or head 27 fits snugly over the eraser 50 socket 28 so as not to be ordinarily removed when removing the operating member C.

The propelling mechanism B which is made up of the sections consisting of the threaded tubular member 16 and the operating member C which is composed of the longitudinally slotted member 17 are removable from the casing A collectively. In removing the parts collectively the members 16 and 17 together with the connecting parts 60 are removed in their entirety from the casing A while the operating member C may be selectively removed from the propelling mechanism B either when the same is held in the casing A or when the propelling mechanism in its entirety has been removed 65

from the barrel. Thus it is obvious that the propelling mechanism can be removed collectively from the barrel A without separating the sections if desired or the operating member C can be selected to be removed 70 independent of the other sections of the propelling mechanism. The term "selective" is particularly adapted to the part C of the propelling mechanism by reason of the fact that it can be removed or selected from the other parts of the propelling mechanism when the propelling means is held in the barrel or when it is removed from the same. 75

I claim:

1. A pencil comprising an enclosing casing, a sectional lead propelling mechanism collectively or selectively removable from the said casing, and a spring sleeve lock adapted to be compressed in said lead propelling mechanism to lock and prevent the free longitudinal movement of the separable portion of said lead propelling means. 80

2. A pencil including a lead propelling mechanism, comprising a tubular operating member positioned within a tubular threaded member, said members being collectively or selectively removable from the pencil casing and a resilient locking means interposed between said operating member and said threaded member in a manner to form a lock to hold said operating member against free longitudinal movement in said threaded member. 90

3. A pencil including a casing, a lead propelling means, comprising separable sections and a spring sleeve carried by one of said sections adapted to form a lock to prevent longitudinal movement of said sections when in operating position in said pencil. 100

4. A pencil comprising a casing, a tubular threaded member removably positioned within said casing and spaced therefrom to form a chamber thereabout, an unthreaded portion on one end of said member, an operating member freely rotatable in said threaded member in a manner to propel or repel a marking lead, and a spring sleeve lock adapted to hold said operating member against longitudinal movement by engaging under spring tension the unthreaded portion of said threaded member. 110

5. A pencil having a casing, a lead propelling means comprising separable sections removable collectively or selectively from said casing and a tubular spring lock carried by one of said sections and interposed therebetween in a manner to form a lock to prevent free longitudinal movement of the separable sections during operation, but to allow free rotatable movement between said sections. 120

6. A spring lock for separable sections of a pencil lead propelling means, including a divided sleeve which is adapted to engage between the separable sections when 125 130

compressed to lock the sections against free separation, but freely rotatable for the purposes specified.

7. In a mechanical pencil having a casing, 5 a lead propelling means formed of separable sections adapted to be contained in said casing in a manner to be removed collectively or selectively and a tubular locking member adapted, when compressed between 10 said sections, to form a lock to prevent the free separation of said sections during the operation of said propelling means.

8. A mechanical pencil comprising a casing, 15 a separable sectional lead propelling mechanism within said casing, a lead carrier adapted to form frictional resilient means between said sections and a tubular locking member carried by one of said sections adapted to prevent longitudinal movement 20 of said sections in relation to each other during the operation of said lead carrier.

9. A pencil, the combination of a casing, 25 a threaded tubular member positioned within and spaced from said casing to form a circular chamber thereabout, a tubular operating member adapted to extend through said threaded member, an unthreaded portion on said threaded member, a lead carrier adapted to form frictional resilient means between said threaded member and said operating member, and a resilient sleeve 30 freely rotatable on said operating member adapted to engage said unthreaded portion on said threaded member to prevent longitudinal movement of said operating member in relation to said threaded member when said operating member is rotated to move said lead carrier longitudinally in said 40 threaded member.

10. A mechanical pencil, including a lead propelling means comprising sections adapted to be separated from each other, a lead carrier having transverse compensating 45 means to form frictional contact between said sections and a sleeve rotatably attached to one of said sections against longitudinal movement in a manner to form frictional contact between said sections to prevent longitudinal movement of said sections in relation to each other when said lead carrier is moved longitudinally in said propelling means.

11. A mechanical pencil, including a severable lead propelling mechanism, a releasable lead carrier in said propelling mechanism adapted to move longitudinally to house the marking lead when more than writing pressure is exerted against the lead 60 and a spring locking sleeve interposed between the sections of said propelling means to prevent separation of said sections when said lead carrier is moved longitudinally.

12. A pencil, including a casing, adapted 65 to house a separable lead propelling means,

a compensating lead carrier in the lead propelling means adapted to releasably hold a marking lead in writing position and a tubular member adapted to lock the sections of said lead propelling means against free separation or longitudinal movement during the longitudinal movement of said lead carrier.

13. A pencil including an engageable portion, lead propelling means, and an attachment for the latter comprising an element rotatably carried by a part of the propelling means and adapted to frictionally engage said engageable portion to hold said element against rotation and form a frictional retaining means for said part.

14. A pencil including lead propelling means, and a lock for said means comprising a spring sleeve rotatably held to a part of the propelling means and fixed against longitudinal movement relatively thereto.

15. A mechanical pencil having a sectional lead propelling means comprised of two main members, one of said members carrying a spring locking sleeve element freely journaled to rotate thereon and the other member adapted to receive said locking member to hold the members of said propelling mechanism freely rotatable and against longitudinal movement, but separable from each other.

16. A pencil comprising a casing, a cap tube, a contractile and expandable bearing sleeve on the cap tube and insertable therewith into the casing, said bearing sleeve being arranged to be contracted onto the cap tube by its insertion into the casing, and lead-feeding mechanism carried by the tube.

17. A pencil comprising a casing, a cap tube, a longitudinally divided contractile and expandable bearing sleeve on the cap tube and insertable therewith into the casing, said bearing sleeve being arranged to be contracted onto the cap tube by its insertion into the casing, and lead-feeding mechanism carried by the tube.

18. A pencil comprising a casing, a cap tube, a longitudinally divided contractile and expandable bearing sleeve on the cap tube and insertable therewith into the casing, said bearing sleeve being arranged to be contracted onto the cap tube by its insertion into the casing, means on the cap tube for holding the bearing sleeve against axial movement thereon, and lead-feeding mechanism carried by the tube.

19. A pencil comprising a casing, a cap tube, a longitudinally divided contractile and expandable bearing sleeve on the cap tube and insertable therewith into the casing, said bearing sleeve being arranged to be contracted onto the cap tube by its insertion into the casing, means on the cap tube for holding the bearing sleeve against axial movement thereon, said bearing sleeve and

casing having yielding interlocking engagement to hold the bearing sleeve and cap tube against axial movement in the casing, and lead-feeding mechanism carried by the 5 tube.

20. A pencil comprising a casing, a cap tube, a longitudinally divided contractible and expandible bearing sleeve on the cap tube and insertable therewith into the casing, 10 said bearing sleeve being arranged to be contracted onto the cap tube by its insertion into the casing, means on the cap tube for holding the bearing sleeve against axial movement thereon, said bearing sleeve and 15 casing having yielding interlocking engagement to hold the bearing sleeve and cap tube against axial movement in the casing, the lower end of the bearing sleeve being beveled for engagement with the casing to cause the 20 same to be contracted thereby during its insertion into the casing, and lead-feeding mechanism carried by the tube.
21. A pencil comprising a casing, a cap tube in the casing, a cap tube extension telescoped onto the cap tube, a bearing sleeve in 25

which the cap tube is rotatively mounted, said bearing sleeve being held by the casing against rotation and held against axial movement on the cap tube by the cap tube extension and a bead on the cap tube, and 30 lead-feeding mechanism carried by the cap tube.

22. A pencil including an engageable portion, lead propelling means, and an attachment interposed between said engageable portion and a part of the propelling means, and 35 rotatably carried by one of them while frictionally engaging the other against rotation to constitute a frictional retaining means for said part of the propelling means. 40

23. A pencil including an engageable portion, lead propelling means, and an attachment for the latter comprising an element rotatably carried by a part of the propelling means and adapted to detachably engage 45 said engageable portion to hold said element against rotation and form releasable retaining means for the propelling means.

HOWARD L. FISCHER.
